UNITED STATES PATENT OFFICE.

MAX ABRAHAMS, OF NEW YORK, N. Y.

DESIGN FOR AN ACOUSTIC HORN.

Application filed July 26, 1926. Serial No. 18,488. Term of patent 14 years.

To all whom it may concern:

Be it known that I, MAX ABRAHAMS, a citizen of the United States of America, residing at New York city, in the county and State of New York, have invented a new, original, and ornamental Design for Acoustic Horns, of which the following is a specification, reference being had to the accompanying drawing, forming part thereof.

Figure 1 is a side view of the acoustic horn showing my new design; and Fig. 2 is a front view thereof.

I claim:

The ornamental design for an acoustic horn as shown.

MAX ABRAHAMS.
